CLAIM

We claim the ornamental design for a mug, as shown and described.

DESCRIPTION

FIG. 1 is a front perspective view of a mug showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the mug that form no part of the claimed design. The dot dash lines in the drawings represent the bounds of the claims and form no part of the claimed design. The stippling in the drawing shows contrast in appearance.
